DESIGN FOR A WRINGER HEAD FOR WASHING MACHINES

Julian L. Perkins, West Springfield, Mass.

Application January 19, 1934, Serial No. 50,457

Term of patent 7 years

To all whom it may concern:

Be it known that I, JULIAN L. PERKINS, a citizen of the United States, residing at West Springfield, in the county of Hampden and State of Massachusetts, have invented a new, original, and ornamental Design for a Wringer Head for Washing Machines, of which the following is a specification, reference being had to the accompanying drawing, forming part thereof:

Fig. 1 is a plan view of the wringer head showing my new design.

Fig. 2 is a side elevational view thereof, and Fig. 3 is an end elevational view of the wringer head shown in Figs. 1 and 2.

I claim:

The ornamental design for a wringer head for washing machines, substantially as shown.

JULIAN L. PERKINS.
